UNITED STATES PATENT OFFICE.

HANS PETERSEN, OF MINNEAPOLIS, MINNESOTA.

KEYBOARD AND ESCAPEMENT MECHANISM FOR LINOTYPE-MACHINES.

1,098,681.

Specification of Letters Patent.

Patented June 2, 1914.

Application filed October 4, 1911. Serial No. 652,779.

To all whom it may concern:

Be it known that I, HANS PETERSEN, a citizen of the United States, residing at Minneapolis, in the county of Hennepin and State of Minnesota, have invented certain new and useful Improvements in Keyboard and Escapement Mechanism for Linotype-Machines; and I do hereby declare the following to be a full, clear, and exact description of the invention, such as will enable others skilled in the art to which it appertains to make and use the same.

My present invention relates to linotype machines, and has for its object to provide an improved keyboard and escapement mechanism therefor.

To the above ends, generally stated, the invention consists of the novel devices and combinations of devices hereinafter described and defined in the claims.

In the accompanying drawings which illustrate the invention, like characters indicate like parts throughout the several views.

Referring to the drawings, Figure 1 is a view partly in section and partly in diagram showing a portion of an inclined matrix magazine with matrices therein and illustrating my improved keyboard and escapement connections operatively connected thereto; Fig. 2 is a vertical section showing a form of the escapement modified for application to a multiple magazine machine; Fig. 3 is a view partly in plan and partly in section on the line w^o-w^o of Fig. 2, some parts being broken away; Fig. 4 is a view in vertical section showing an arrangement of the keyboard and escapement connections in a vertical magazine; and Fig. 5 illustrates a further modification of the escapement shown in Fig. 4.

Describing first the construction illustrated in Fig. 1, the numeral 1 indicates an inclined magazine which contains the usual matrices 2. The first or lowest matrix is held back by an upright escapement bar 3 which works through suitable guides 4, and the upper end of which is reduced to form an escapement lug or finger 5 that works through an opening in the bottom of the magazine 1 and engages with the upper member of the under lugs of the said first matrix. The escapement proper may, as will hereinafter appear, take different forms.

To actuate the matrix escapement, an escapement actuator, so-called, of materially improved arrangement is employed. This

actuator involves a continuously driven roller or wheel 6, and an eccentric 7. The roller 6 is either applied to or formed as a part of a shaft which is continuously driven and which forms a part of the machine, and preferably this roller is of such length that it will cooperate with the eccentric 7 of all of the several escapement actuators. The said eccentric 7 is shown as in the form of a disk having a serrated edge for engagement with the surface of the driving roller 6, and it is preferably pivoted at 8 to the depending arm of a bell crank 9, which bell crank is pivotally supported at 10, with its horizontal arm engageable with the lower end of the escapement bar 3 and supporting the said bar. The depending arm of the bell crank 9 is provided, in one side, with clearance notch 9^a that is adapted to receive the projecting end of a releasing trigger 11, which, as shown, is substantially in the form of a bell crank pivotally supported at 12. The depending arm of the trigger 11 is operated upon by the ratchet-like teeth or cam surfaces of a cam wheel 13. The finger keys 14 are shown as intermediate pivoted at 15 with their ends engaging notches of a long pawl 16. The upper end of this pawl 16 engages the teeth of the ratchet wheel 13, and the lower end thereof is provided with a longitudinal slot 17 that works on a fixed guide pin 18. The slot 17 limits the stroke of the pawl 16 and permits the slight necessary pivotal movements thereof. The trigger 11 is gravity held, normally in the position shown in Fig. 1 and its extended arm engages the depending arm of the bell crank 9 and holds the eccentric 7 out of contact with the driving rollers 6.

When the key 14 is depressed and the pawl 16 raised, it will impart one step of rotary movement to the ratchet wheel 13, and the latter acting on the trigger 11, will force the extended arm thereof into alignment with the notch 9^a of the bell crank 9. This alignment of the trigger with the notch 9^a releases the bell crank and the escapement bar 3, so that the said bar is permitted to drop far enough to release the first or lowest matrix. This downward movement of the said escapement bar 3 forces the eccentric 7 into contact with the continuously running roller 6, so that by frictional contact with the said roller, the said eccentric will be given one complete rotation. When the radially longest portion of the ec-

centric 7 is brought into contact with the roller 6, it forces the bell crank 9 and the escapement bar 3 back to their normal positions, and the trigger 11, under the action 5 of gravity, assumes its operative position and locks the said parts 9 and 3 in their normal positions.

The time required for the eccentric 7 to make its rotation, and hence, for the escapement bar 3 to make its downward and return movement, is sufficient to permit the release of the first or lowest matrix, but not 10 of the next following matrix, and hence, the escapement lug 5 of the said bar 3 will engage the lower end of the upper lug of the 15 second matrix, which second matrix then, of course becomes the first or lowermost matrix. It will thus be seen that this device insures the release of but one matrix under any one 20 key depression, and it make no difference how long the said key may be held depressed. The escapement actuating mechanism, above described, may be, and preferably is, employed with the multiple magazine 25 and escapement mechanism shown in Figs. 2 and 3. In this multiple magazine machine, the several independent magazines 19 are shown as inclined, and one located over the other, and the escapement bar is 30 made up of a main section 20 and a multiplicity of separate but supplemental sections 21, of which latter, there is one for the corresponding or overlying channel of each magazine. These supplemental sections 35 21 are provided with laterally projecting escapement lugs 22 that work through clearance passages in the bottom of the respective magazines and engage the lugs of matrices in the same manner as do the lugs 40 5 of the escapement bar 3, shown in Fig. 1. The supplemental bar sections 21 may be yieldably held down by gravity or by the action of gravity and the coöperating action 45 of light springs 23. In Fig. 3, the numeral 24 indicates selecting bars, one for each magazine which operate in a known manner to determine the magazine from which matrices will be discharged under actions of the escapement mechanism.

50 In the arrangement illustrated in Fig. 4, the numeral 25 indicates an upright magazine having in one side perforations through which work escapement lugs 26 formed on the upper ends of escapement levers 27, 55 intermediately pivoted at 28 and provided at their lower ends with clearance notches 29. The key 30 is intermediately pivoted and normally engages the lower end of the escapement lever 27, and when the key is 60 depressed, alines with the notches 29 so that the said escapement lever will be retracted under the action of a spring 31, and the first or lowest matrix released. In this arrangement, the continuously driven roller 32 is 65 adapted to be engaged by an eccentric 33

which is journaled in the lower portion of the escapement lever 27.

In the construction illustrated in Fig. 5, the upright magazine 34 is provided with perforations in one side through which the upper and lower ends of a spring-pressed escapement dog 35 are arranged to work. The lower portion of this escapement dog 35 is subject to the upper end of an intermediately pivoted escapement lever 36 70 shown as subject to a spring 37. In this arrangement, the continuously driven roller 38 coöperates with an escapement 39, journaled to the lower end of an escapement lever 36, and the lower end of the said escapement lever, normally, is in a notch 40 of a secondary key lever 41, and is thereby held in its normal or retracted position shown in Fig. 5, against the tension of a spring 37, which latter tends to engage the eccentric 39 with 75 the roller 38. The secondary key lever 41 is connected to, and operated by the main key lever 42. This key lever 42 is subject to a retracted spring 43.

In all forms of the device above described, 80 the escapement device works through the side of the magazine and within a space between the vertically or longitudinally spaced lugs of the first or lowest matrix. In the mechanism shown in Fig. 5, however, the escapement device 35 operates positively and with a two-step movement to release the matrices, while in the other forms, the escapement is timed so that by a single movement, it catches the next matrix. 85

In all forms illustrated, the eccentrics which coöperate with the driving rollers, are gravity-arighted or held in normal position, or in other words, are simply suspended under their own weight, no stops whatever 105 being required to hold the said eccentrics in their normal or inactive rotary positions.

What I claim is:

1. In a linotype machine, a non-repeating mechanically operated key controlled matrix releasing mechanism, including a driving roller, a coöperating eccentric, a key operated cam having a multiplicity of cam surfaces, and a trigger subject to said cam and normally holding said eccentric out of engagement with said roller. 110

2. In a linotype machine, a non-repeating mechanically operated key controlled matrix releasing mechanism, comprising a matrix escapement element, a lever supporting 120 the latter, an eccentric pivoted to said lever, a driving roller coöperating with said eccentric, a trigger normally holding said eccentric disengaged from said driving roller, a ratchet wheel operative as a tripping cam 125 on said trigger, and a key with connections for intermittently rotating said ratchet wheel.

3. In a linotype machine, the combination 130 with a matrix magazine, of a key-controlled

escapement mechanism including a matrix engaging element having its entire matrix engaging portion included within the space between upper and lower lugs of the first or 5 lowest matrix and operative only on the first or lowest matrix.

4. In a linotype machine, a matrix releasing mechanism comprising a continuously running driving roller, an escapement element, a vibratory member arranged to move said escapement element, a loosely suspended eccentric gravity-held with freedom for movements in either direction carried by said vibratory member into and out of engagement with said driving roller, said vibratory member being normally under strain to move said eccentric into engagement with said driving roller, and a key controlled element normally holding said vibratory 10 member in a retracted position with said eccentric disengaged from said driving roller.

5. In a linotype machine, a matrix releasing mechanism comprising a continuously running driving roller, an escapement element, a lever arranged to move said escapement element, a loosely suspended eccentric gravity-held with freedom for movements in either direction carried by said 15

lever into and out of engagement with said driving roller, said lever being normally 30 under strain to move said eccentric into engagement with said driving roller, and a key-controlled element normally holding said lever in a retracted position with said eccentric disengaged from said driving 35 roller.

6. In a linotype machine, a non-repeating machine power operated key-controlled matrix escapement mechanism including an escapement dog adapted to be moved to release a matrix, means for restoring said escapement dog to normal position and for holding the same in its normal position, and a releasing key having connections for throwing said restoring means into action, 40 the said machine including automatic means for completing the restoring action thereof, regardless of whether or not said key is held depressed.

In testimony whereof I affix my signature 45 in presence of two witnesses.

HANS PETERSEN.
